UNITED STATES PATENT OFFICE.

EMMA R. LEE THAYER, OF HASTINGS - UPON - HUDSON, NEW YORK, ASSIGNOR TO
BRUGUIER CHEMICAL CO., OF NEWARK, NEW JERSEY, A CORPORATION OF NEW
JERSEY.

DESIGN FOR A CAN.

41,028.

Specification for Design.

Patented Dec. 6, 1910.

Application filed July 16, 1910. Serial No. 572,384. Term of patent 14 years.

To all whom it may concern:

Be it known that I, EMMA R. LEE THAYER, a citizen of the United States, and a resident of Hastings-on-the-Hudson, county of Westchester, State of New York, have invented a new, original, and ornamental Design for a Can, of which the following is a specification.

Reference is to be had to the accompanying drawings in which—

Figure 1 is a front elevation of a can showing my new design; Fig. 2 is a rear elevation thereof and Fig. 3 is a plan view thereof.

The design comprises a panel having the form of a fleur de lis and surrounded by a

floral border of pansy design, a flower appearing in the upper point of the fleur de lis and a panel having the form of an inverted shield also surrounded by a similar floral border. Two flowers of pansy shape similar to those in the border appear on the curved horizontal surfaces of the can to either side of the neck and are connected by circular bands surrounding said neck.

I claim:

The ornamental design for a can as shown and described.

EMMA R. LEE THAYER.
